DESIGN FOR MEDALS.

Specification forming part of Design No. 7,827, dated November 3, 1874; application filed September 14, 1874.
[Term of Patent 3½ years.]

To all whom it may concern:

Be it known that we, T. ROLLASON HARTELL and JOHN LETCHWORTH, of Philadelphia, in the county of Philadelphia and State of Pennsylvania, have invented a certain new Design for Medals; and we do hereby declare the following to be a full, clear, and exact description of the same.

Our design for a medal consists of a view of the art-gallery of the Centennial Exposition, to be held in the city of Philadelphia, Pennsylvania, in the year 1876, as shown in the accompanying fac-simile.

The figure in the accompanying fac-simile is a perspective view of the art-gallery, which

design is applied to one side or both sides of said medal in any suitable and appropriate manner.

What we claim is—

The design for a medal, herein described, and shown in the accompanying photograph.

In testimony that we claim the foregoing we have hereunto set our hands this 12th day of September, 1874.
